(57) **CLAIM**

The ornamental design for a gym bag, as shown and described.

DESCRIPTION

FIG. 1 is a 3/4 perspective view of a gym bag.

FIG. 2 is a front elevational view of FIG. 1.

FIG. 3 is a rear elevational view of FIG. 1.

FIG. 4 is a left side elevational view of FIG. 1.

FIG. 5 is a right side elevational view of FIG. 1.

FIG. 6 is a top plan view of FIG. 1.

FIG. 7 is a bottom plan view of FIG. 1.

FIG. 8 is a top open perspective view of FIG. 1.

FIG. 9 is a top open plan view of FIG. 1; and,

FIG. 10 is a cross sectional view taken along the lines indicated in FIG. 6.

The dotted lines illustrate portions of the gym bag. The dashed lines illustrate environment. None of the broken lines form part of the claimed design.
